(57) **CLAIM**

The ornamental design for a tattoo needle cartridge, as shown and described.

DESCRIPTION

FIG. 1 is an enlarged front perspective view of the tattoo needle cartridge showing my new design;

FIG. 2 is a front view thereof;

FIG. 3 is a back view thereof;

FIG. 4 is an enlarged top view thereof;

FIG. 5 is an enlarged bottom view thereof;

FIG. 6 is a left side view thereof; and,

FIG. 7 is a right side view thereof.

The broken lines depict portions of the tattoo needle cartridge that form no part of the claimed design.
